MACHINE FOR OPERATING ON TEXTILE THREADS

Robert Robertson, Pawtucket, R. I.

Application November 14, 1933, Serial No. 697,910

7 Claims. (Cl. 28—28)

This invention relates to a machine more particularly designed for operating on textile threads where it is desired that these threads be not stopped during their operation because of possible injury to the same and is particularly illustrated in this application as applied to a warp-sizing machine, which I will describe in detail altho uses on other similar machines will be understood as being contemplated by 10 this invention.

One of the objects of the invention is to provide a means by which the warps during sizing will be constantly driven so as to prevent injury of the same from the heating of the drying drums.

Another object of the invention is the provision of driving means to drive the warps at a relatively slow rate of speed while the ends are being pieced, without detrimentally affecting the 20 relatively high speed operation of the warps during the period when no piecing up of the ends or other work is necessary.

Another object of the invention is the provision of a relatively fast and relatively slow rate 25 of speed both positively and continuously, connected to a drive for the machine with an arrangement so that when the relatively high speed drive is used the relatively slow speed drive will run free and will pick up the load again only when the machine is relieved from 30 being driven at this higher rate of speed.

A further object of the invention is the provision of relatively slow speed electric driving 35 motor to be used in connection with a relatively high speed driving motor with a positive connection of the slow motor to the drive for the machine thru an overrunning clutch so that so long as the high speed motor is in operation the slow motor will be ineffectual but 40 as soon as the high speed motor is discontinued then the drive will be carried on by the slow speed motor driving thru the overrunning clutch.

With these and other objects in view, the invention consists of certain novel features of construction, as will be more fully described, and particularly pointed out in the appended claims.

In the accompanying drawings:

Fig. 1 is a side elevation in a more or less diagrammatic arrangement of a warp-sizing machine, illustrating particularly the drives and the connection of my slow speed motor to the main driving gear.

Fig. 2 is a top plan view of the two speed motors and the driving connections showing a fragmental portion only of the machine.

Fig. 3 is a diagrammatic view showing the lead of the warps from the several warp beams 60 to their final packaging beam.

Fig. 4 is a sectional view thru the overrunning clutch.

Fig. 5 is a section on line 5—5 of Fig. 4, illustrating one means of providing an overrunning clutch.

Fig. 6 is a diagrammatic view illustrating the relative position of the machine and the several stations from which my control may be operated.

In practice, it has been found that in sizing warps which are of rayon, celanese or other synthetic formation, in running them upon the usual cotton warping machines they frequently become detrimentally affected by a stopping of the machine for piecing the ends and allowing these synthetic fibers to contact with the drying drums without moving thereacross, altho in cotton warps when used on the machine no such detrimental action occurs.

In the operation of such a machine, however, the operators cannot piece up the threads during the usual relatively high rate of travel of the warps thru the machine and in order to piece up the threads it was necessary to stop the machine or to slow it down thru a Reeves drive or the like, requiring a rather lengthy operation and requiring a further similar length operation to speed up the machine to the required travel, and in order to speed up the operation of filling the beam and also provide a positive means whereby the warp will not stop in its travel over the heating drying drums, I have provided a slow speed motor and

connected it positively to the drive mechanism of the machine thru an overrunning clutch so that the relatively fast drive of the machine may be shut off and this slow speed motor will pick up and drive the warps over the heated drying drums, whereby the same will not become injured as would occur by stopping the machine and yet the movement is so slow that the operator may piece up the ends during the travel of the yarn from the machine and I have provided remote controls for the high speed motor located at various convenient points about the machine so that as soon as all the ends are pieced up the operator may just push a button to bring into action the high speed motor and cause the yarn to travel along at a high rate of speed until the operator notices a break then he may cause the machine to slow down almost instantly after this break occurs and again after repaired speed up the machine. This action occurs without any undue strain on the yarn and materially speeds up production and the arrangement which I have provided is so simple that it is comparatively inexpensive to install for its complete and positive actuation of the machine; and the following is a more detailed description of the present embodiment of this invention illustrating the preferred means by which these advantageous results may be accomplished:

Fig. 1 is a side elevation in a more or less diagrammatic arrangement of a warp-sizing machine, illustrating particularly the drives and the connection of my slow speed motor to the main driving gear.

Fig. 2 is a top plan view of the two speed motors and the driving connections showing a fragmental portion only of the machine.

Fig. 3 is a diagrammatic view showing the lead of the warps from the several warp beams to their final packaging beam.

Fig. 4 is a sectional view thru the overrunning clutch.

Fig. 5 is a section on line 5—5 of Fig. 4, illustrating one means of providing an overrunning clutch.

Fig. 6 is a diagrammatic view illustrating the relative position of the machine and the several stations from which my control may be operated.

In practice, it has been found that in sizing warps which are of rayon, celanese or other synthetic formation, in running them upon the usual cotton warping machines they frequently become detrimentally affected by a stopping of the machine for piecing the ends and allowing these synthetic fibers to contact with the drying drums without moving thereacross, altho in cotton warps when used on the machine no such detrimental action occurs.

In the operation of such a machine, however, the operators cannot piece up the threads during the usual relatively high rate of travel of the warps thru the machine and in order to piece up the threads it was necessary to stop the machine or to slow it down thru a Reeves drive or the like, requiring a rather lengthy operation and requiring a further similar length operation to speed up the machine to the required travel, and in order to speed up the operation of filling the beam and also provide a positive means whereby the warp will not stop in its travel over the heating drying drums, I have provided a slow speed motor and

With reference to the drawings, I have indicated in Fig. 1, a more or less diagrammatic view of the framework consisting of uprights 10 and horizontals 11, 12 and 13 upon which the 5 bearings for the different rotating parts of the machine are mounted. The warp threads 14 are drawn from a plurality of section beams 15, 16, 17 etc., thru a reed 18 which may be adjustable over the bars 19 and 20, between which 10 there may be a lease 21, thence thru the slashing rolls 22 and 23, where a sizing 24 in a trough 25 is applied by means of a roll 26, thence over a series of drying drums 27, 28, 29, 30 and 31, each of which is provided with steam sufficient 15 to heat it to the desired degree, around substantially 200° Fahrenheit.

Steam pipes to each of the drums are illustrated generally at 32 and the usual siphon arrangement for picking up the steam condensation and extracting it from the drums is provided which is not shown in this disclosure. The warps travel over a guide roller 33 and are then reeled on a warp beam 34, which has adjustable heads to accommodate the varying 25 widths in which the beam is to be formed.

The main driven element or gear 35 is mounted on the main drive shaft 36 of the machine upon which there is a clutch 37 for controlling the operation of the machine. This 30 clutch is operated by a shift lever 38 extending out to a handle 39 for convenient manipulation. Upon this driven shaft 36, there is a pulley 40 which drives pulley 41 by means of a belt 42 which affords a slip friction connection in the 35 conventional way as shown in Patent No. 1,540,-265 dated June 2, 1925 and which in turn drives gear 43 and gear 44 connected to the packaging warp beam 34.

There is also mounted upon the main drive 40 shaft 36 a gear 45 which drives gear 46 on the same shaft with gear 47, which latter in turn engages the teeth 48 on the heated drum 31 from which the remaining drums are driven thru suitable pinions 49 and 50 transmitting motion 45 throughout the train. The slashing rolls are driven from the gear 60 by gear 61, pulley 62, belt 63, gears 64 and 65, all of which drive is more or less conventional in a machine of this character.

50 A relatively high speed motor 70 is mounted upon a bracket 71 on the frame of the machine and drives gear 72 which meshes with the main drive gear 35 thru a Reeves drive consisting of V pulleys 73, 74 with a V belt 75 between them, pulley 74 being driven by gear 76 on shaft 77 and belt 78 connected with gear 79 on the motor 70. The effective speed, of course, of this motor may be varied by reason of the adjustment of the Reeves drive to separate the pulleys 73 and 74, 60 as desired.

A relatively slow speed motor 80 is provided with suitable helical reducing gears to drive shaft 81 upon which there is mounted a gear 82 directly engaging the main driven element or gear 35. This gear 82 is connected to the shaft 81 thru an overrunning clutch designated generally 83 and more fully illustrated in Figs. 4 and 5.

70 The shaft 81 is reduced as at 84 at its end, providing a shoulder 85. The overrunning clutch designated generally 83 consists of a casing 86 in which there is provided a hardened bushing 87, which directly engages and rotates on the smaller portion 84 of the shaft and is spaced 75 from the shoulder 85 by a washer 91. Upon this

casing, there is mounted a gear 82, which is keyed to the casing by the key 88 which may enter thru the keyway 89 in the casing 86. There is also mounted on this casing in engagement with this gear 82, a sleeve 90 which tightly fits about the casing and assists in holding the gear in position. Within the sleeve 90 there is provided a ball bearing 92 which is mounted upon the larger part 81 of the shaft. The part 93 of this ball bearing snugly fits the shaft 81 while the part 94 snugly engages the sleeve 90 with the balls 95 rotatably located between these parts. Thus the casing is so mounted that it may be rotated relatively to the shaft, if such force is applied to it to cause it to have this movement. 15

The casing 86 also has a unit tightly fitting therein, consisting of a cylindrical shell 96 having two inwardly extending fins 97 between which there are mounted rollers 98, prevented from axial movement by these fins, while there 20 is a drum 99 keyed as at 100 to the shaft 84 which has a plurality of notches 101 in it in each of which one of the rollers 98 is located. Each of these notches has a surface 102 which extends towards the shell 96 so that should the roller 25 move along this surface towards the shell it would be wedged and bound by its engagement therewith, while when it is against the abutment 103 of the notch it may rotate freely in the notch, whereby free relative rotation of these 30 parts is permitted. A cap 104 is screwed into the end of the casing to house these parts therein.

The arrangement is thus such that if the shaft 31 rotates in the direction of the arrow A, or 35 clockwise as in Fig. 5, the rollers will move to binding position and will drive the casing 86 the gear thereon and any parts to which it is connected; while if the casing were driven in the direction of arrow A faster than the shaft 81, there would be a free rotation of the parts by reason of the rolling of the rollers 98. 40

The machine as a whole designated 105 in Fig. 6 has any desired number of stations 106, 107 located at convenient points about the machine 45 for the control thereof. At each station there is a two button switch. Pressure on one button 108 will cause the high speed motor 70 to stop by reason of disconnecting the power from the main line 110, while when so disconnected pressure on the other button 109 will cause the energy to be supplied thru suitable relays 119 and switch 112, as illustrated in the wiring diagram in Fig. 6. This relay is shunted to be energized 55 to hold the switch to motor 70 closed until the line is broken by switch 108 when the relay lets go and switch 111 is moved out of closed position by suitable springs or weights. 60

Operation

In the operation of this machine, I cause the constant drive of the motor 80 at a speed which will cause the warps to move thru the machine at a slow rate of speed, which will be sufficient to prevent injury by the heat from the drying drums and the motion will be sufficiently slow so that the operator can piece up the ends in the space between the section beams 15, 16 and 17 and the reed or at other points of the machine as they pass therethrough. When the warps are intact the relatively high speed motor is thrown into operation at one of the stations 106 or 107 and will pick up the load and cause the warps to travel therethrough at a high rate of speed. This high speed drive will 75

be free from the low speed motor by reason of the overrunning clutch described permitting this action without rotation of the helical gears of the slow speed motor which at the high rate 5 speed would be detrimental to their life.

Should an operator observe a break in any of the ends, he will shut off the high speed motor permitting the slow speed motor to cause the warps to travel slowly thru the machine and 10 allow sufficient time for any broken down ends to be pieced up after which the high speed motor will again be caused to pick up the load and move the warps at a high rate of speed, which makes unnecessary the slowing down of the machine 15 thru the Reeves drive which is a lengthy operation and also eliminates the necessity of the operator shutting off the machine by the clutch 37 which will injure synthetic yarns. This control of the motor 70 may be from any 20 point about the machine, which I have illustrated at 106 and 107, thus permitting nicer control of the machine than has heretofore been possible.

It will be remembered that machines of this 25 character are some 25 to 30 feet long and the operator has to walk about the same to any single point which cannot be accomplished quickly.

Both drives are positively connected to the 30 main drive gear and main drive shaft at all times. When the high speed motor is shut off and the slow speed motor is operating the machine, the field of the motor 70 is dead allowing the armature to turn freely while, of course, 35 the overrunning clutch permits the operation at the faster rate of speed without similarly driving the motor 80.

The foregoing description is directed solely 40 towards the construction illustrated, but I desire it to be understood that I reserve the privilege of resorting to all the mechanical changes to which the device is susceptible, the invention being defined and limited only by the terms of the appended claims.

45 I claim:

1. In a warp sizing machine having a slashing box and highly heated drums for drying the warp threads, a warp beam, a main driving gear, a relatively slow constantly driven shaft geared thereto thru an overrunning clutch, 50 means for driving said shaft, a relatively fast intermittently driven shaft geared to the main driving gear to pick up the load of the machine and drive it without affecting the slow driving means on the other side of said clutch, and means separate from the first driving means for driving said intermittently driven shaft.

2. In a warp sizing machine having a slashing box and highly heated drums for drying 60 the warp threads, a warp beam, a main drive gear, a relatively slow constantly driven electric motor geared to said main drive gear thru an overrunning clutch, an independent relatively fast electric motor geared to the main 65 drive gear to pick up the load of the machine and drive it without affecting the slow motor, and a plurality of means remotely located from the fast motor for controlling the operation thereof.

70 3. A warp sizing machine comprising a rotary means on which to wind the warp, rotary means having a slip friction connection with and adapt-

ed to transmit rotation to the first means, and rotary heated means anterior to the first means resisting advance of the warp, a rotary driven element driving the second and third means, means for driving said driven element at a relatively fast rate of speed, means for driving said driving means at a relatively slow rate of speed, and means for controlling the operation of said relatively fast driving means, said relatively slow driving means operating continually with 10 an overrunning clutch interposed in its drive to permit the relatively faster drive to operate and to pick up the load when the driven element slows down to a predetermined speed.

4. A warp sizing machine comprising a rotary 15 means on which to wind the warp, rotary means having a slip-friction connection with and adapted to transmit rotation to the first means, and rotary heated means anterior to the first means resisting advance of the warp, a rotary 20 driven element driving the second and third means, a constantly rotating driving element, low-speed means to transmit rotary motion from the driving to the driven element including an overrunning clutch, and high speed means connected to transmit rotary motion to said driven 25 element, and means for rendering operative or inoperative said high speed means.

5. A warp sizing machine comprising a rotary 30 means on which to wind the warp, rotary means having a slip-friction connection with and adapted to transmit rotation to the first means, and rotary heated means anterior to the first means resisting advance of the warp, a rotary 35 driven element driving the second and third means, a constantly rotating driving element, low-speed means to transmit rotary motion from the driving to the driven element including an overrunning clutch, high speed means connected to transmit rotary motion to said driven element, 40 and means for selectively rendering said high speed drive operative or inoperative.

6. A warp sizing machine comprising a rotary 45 means on which to wind the warp, rotary means having a slip friction connection with and adapted to transmit rotation to the first means, and rotary heated means anterior to the first means resisting advance of the warp, a rotary driven element driving the second and third means, a 50 constantly rotating low speed driving shaft transmitting rotary motion to said driven element thru an overrunning clutch, and a high speed rotating shaft operatively connected to said driven element, and means for rendering operative or inoperative said high speed shaft.

7. A warp sizing machine comprising a rotary 55 means on which to wind the warp, rotary means having a slip-friction connection with and adapted to transmit rotation to the first means, and rotary heated means anterior to the first 60 means resisting advance of the warp, means for constantly driving said second and third means at selectively relatively fast or slow rates of speed including a fast rotating shaft and a slow 65 rotating shaft, a common driven element connecting said second and third means to said shafts and an overrunning clutch for automatically disconnecting the driven element from the slow rotating shaft when the fast rotating shaft is operative, and means for rendering operative 70 or inoperative said fast rotating shaft.

ROBERT ROBERTSON.
